DESIGN FOR A REFRIGERATOR

William Archibald Welden, Stamford, Conn., assignor to Harder Refrigerator Corporation, Cobleskill, N. Y., a corporation of New York

Application January 28, 1937, Serial No. 67,315

Term of patent 3½ years

To all whom it may concern:

Be it known that I, William Archibald Welden, a citizen of the United States, residing at Stamford, county of Fairfield and State of Connecticut, have invented a new, original, and ornamental Design for a Refrigerator, of which the following is a specification, reference being had to the accompanying drawing forming a part

thereof in which Fig. 1 is a perspective view of the refrigerator, showing my new design; and Fig. 2 is a top plan view thereof.

I claim:

The ornamental design for a refrigerator as shown.

WILLIAM ARCHIBALD WELDEN.
